SUCTION CLEANER

Vernon E. Carlson, Canton, Ohio, assignor to The
Hoover Company, North Canton, Ohio, a cor-
poration of Ohio

Application January 26, 1939, Serial No. 252,885

10 Claims. (Cl. 15—16)

The present invention relates to suction cleaners in general and more particularly to a new and novel motor ventilating system in a suction cleaner. More specifically the invention comprises a new and novel arrangement of parts in a suction cleaner by which the heat generated by cleaner motor operation is removed in a new and novel manner.

It is an object of the present invention to provide a new and improved suction cleaner. It is another object of the invention to provide a new and improved motor cooling system in a suction cleaner. A further object of the invention is to provide a new and improved system of ventilating passageways for motor cooling in a suction cleaner. A still further object of the invention is to remove the heat generated by the electric motor in cleaner operation by air which is conducted through a system of passageways arranged in a new and novel manner. A still further object of the invention is to provide a motor and light cooling system in a suction cleaner which is new and novel in its arrangement and superior in its operating characteristics. These and other more specific objects will appear upon reading the following specification and claims and upon considering in connection therewith the attached drawing to which they relate.

Referring now to the drawing in which a preferred embodiment of the invention is disclosed:

Figure 1 illustrates a side elevation of a modern suction cleaner embodying the present invention with certain parts of the cleaner casing broken away.

Figure 2 is a view in perspective of the cleaner in Figure 1 with certain parts of the cleaner broken away to show more clearly the motor ventilating system.

Suction cleaners today embody electric motors which drive the suction creating means of the cleaner and the surface agitating means. Modern cleaners also embody headlights which function to illuminate the surface covering undergoing cleaning in front of the cleaner that the operator may more easily observe that covering. Such cleaner motors are generally of high speed characteristics but regardless of the exact type all have in common the characteristic of generating heat when in operation and to obtain efficient operation and long life this heat must be removed. As the light of the headlight is usually positioned near the cleaner motor and as it also generates heat, it is desirable that the headlight heat also be removed to prevent its radiation to the motor.

The use of motor cooling air is of course extremely old and it has long been the practice to drive or force a stream of cooling air over the motor windings for the purpose of conduct-

ing therefrom the inherent heat of operation. It has been the practice to draw the cooling air through the motor by an auxiliary fan which is motor driven and to exhaust that air from the motor through the headlight aperture and over the cleaner nozzle. Because of the relatively large amount of heat which must be removed the volume of air and the speed of its travel is relatively great and it has been found that in some instances the stream of air exhausting through the headlight aperture facing forwardly of the cleaner has interfered with the cleaning effectiveness of the suction nozzle. Also, the air stream exhausted into the surrounding air has been found to carry the noise of the cleaner motor operation.

In the motor cooling system constructed in accordance with the present invention motor cooling air is drawn over the cleaner motor, is exhausted past the cleaner headlight, and passes downwardly through the cleaner casing to be exhausted into the atmosphere on the underside of the cleaner at a point at which it cannot interfere with the cleaning operation and at which any sound which it conducts will be muffled by the cleaner body and the adjacent covering to a desirable extent.

Referring now to the drawing in which a preferred embodiment of the invention is illustrated there is found a modern suction cleaner the main casing of which comprises a nozzle 1 of double wall construction, the inner wall being indicated by the reference character 2. A fan chamber 3 is interiorly connected to the nozzle 1 by an air passageway 4 which is preferably formed integrally with the inner wall 2 of the nozzle 1 excepting its underside which is formed by a removable bottom plate 5. The rear nozzle lip 6 is formed upon plate 5 while the front nozzle lip 7 is formed integrally with the nozzle. The main casing is completed by overhanging side walls or skirts 8 which extend around the sides of the fan chamber 3 to the rear of the cleaner where they extend along the exhaust outlet 9 to which is removably attached, by manually operable means 10, a filter bag 11.

A suction-creating fan 13 is positioned within the fan chamber 3 and functions in the operation of the cleaner to draw air through the nozzle 1 and to exhaust it through the exhaust outlet 9 into the filter bag 11 where the foreign material is removed. Cooperating with the cleaning air actuated by the suction-creating fan 13 is a rotary agitator 14 of a common and well known design which is positioned within the nozzle 1 and which is adapted to contact a surface undergoing cleaning between the lips 6 and 7. Agitator 14 is rotated by a power-transmitting belt 15 which is driven by the same source of power that drives the suction creating fan 13.

The external construction of the cleaner is

completed by the motor hood 17 which is positioned on the main casing of the cleaner above the nozzle 1, fan chamber 3 and exhaust outlet 9 and overlies in part the side skirts 8. Motor hood 17 encloses the driving motor which will hereinafter be described in detail which drives the suction-creating fan 13 and the agitator 14.

The entire cleaner is movably supported by front wheels 18 which are positioned at the sides of the air passageway 4 and under the skirts 8, and by rear wheels 19 and provide means by which the operator can readily propel the machine by a force exerted through a pivoted handle which is partially shown at 20.

The motor which drives the suction-creating fan 13 and the belt 15 connected to the agitator 14 is positioned within the motor hood 17 immediately above the fan chamber 3 and comprises an armature 23 which is rotatably supported at its upper and lower ends by suitable bearing means, the upper bearing being indicated at 24. The motor stator 25 is supported by a motor bottom plate 26 formed with upright side walls which surround the stator 25 and seat it. As the plate is of insulation material, such as Bakelite, the stator can be mounted directly thereon without intermediate insulation. An upper casing section 27, also of insulating material such as Bakelite, is largely of a smaller diameter than the vertical wall of the bottom plate 26 and is formed with a peripheral flange 28 which seats directly upon the top of that plate being suitably secured thereto by screws 29. Near its top, upper casing section 27 is formed with an internal horizontal wall 30 which encloses the motor rotor to provide above itself a ventilating fan chamber, the upper side of which is formed by the removable metal plate 31 which carries the motor bearing 24 and which is secured to the section 27 by screws 32. The motor ventilating fan 33 carried by the rotor 28 is positioned within this chamber.

Formed upon the Bakelite motor bottom plate 26, and more specifically upon the forward side thereof exteriorly of the vertical wall which seats and encloses the stator 25, is a platform 34 which seats a removable headlight bulb 35. The curved forward wall of platform 34 is spaced from the bulb-carrying portion of the platform and is connected thereto by a series of integral radially extending vertical webs 36. These vertical connectors 36 define openings in the platform 34 which lead directly to a port 38 formed below the platform in the top wall of the main casing of the cleaner and specifically in the outer wall of the nozzle thereof. Port 38 connects directly to the space between the outer wall of the nozzle and its inner wall 2 and also directly to the underside of the cleaner casing as defined by the space between the surrounding skirts 8 and the air passageway 4. In fact it most directly connects to the space defined by the skirts 8 which could be called the wheel pockets as the front wheels 18 are positioned therein.

The motor hood 17 is cut out above the forward curved wall of the platform 34, as indicated at 40, to provide a headlight opening forward of the bulb 35. There is positioned in this opening and between the hood and the curved front wall of the platform a transparent window 41 of material such as Celluloid through which light rays from the bulb 35 may be directed forwardly of the nozzle and onto the surface covering undergoing cleaning. Window 41

is suitably retained by grooves in the edges of the opening.

An air passageway is formed from the fan chamber at the top of the motor casing by cooperating vertical walls 42 and 43 on the motor hood 17 and the casing section 27, respectively. These vertical side walls cooperate to provide a passageway which leads directly from the exhaust outlet of the ventilating fan chamber to the top of the platform 34 and in which is positioned the headlight bulb 35.

Inlet ports are formed for the motor cooling air in the lower edge of the motor hood, as indicated at 45, and in the upper edge of the bottom plate 26 as indicated at 46. The air, of course, first enters thru the ports 45 and then passes thru the openings 46 to gain direct contact with the motor windings. It is to be noted that the exhaust passageway formed by the walls 42 and 43 is sealed from the air passing around the motor casing and between the ports 45 and 46.

The operation of the cleaner designed in accordance with the present invention is as follows:

With the cleaner in operation and the motor rotating the suction-creating fan 13 creates a flow of air through the nozzle, fan chamber and exhaust outlet into the dust bag 11. The suction within the nozzle 1 lifts the surface covering undergoing cleaning into contact with the agitating elements of the rotating agitator 14 which dislodge from that covering the embedded foreign material which is then carried away by the air stream to the dust bag. This is as in the usual cleaner. The rotation of the motor generates heat and this heat is carried away by cooling air which is drawn into the motor hood through the ports 45 and into the motor casing through the side ports 46 formed in the lower motor bottom plate 26. This air, drawn by the motor driven ventilating fan 33, passes upwardly over the rotor and stator into the ventilating fan chamber to be exhausted therefrom into the passageway formed by the cooperating vertical walls 42 and 43 of the motor hood and the casing section 27. The air in this exhaust passageway passes downwardly along the side of the motor casing, past the headlight bulb 35, through the openings defined by the vertical webs 36 of the platform 34 and downwardly through the exhaust port 38 into the space between the outer nozzle wall and the top wall of air passageway 4. The air there divides, part going to each side of the passageway adjacent the wheels 18. The air is downwardly deflected at the rear of the nozzle by the skirts 8 and any sound carried thereby is muffled by reflection against the surface covering undergoing cleaning and by the shielding action of the casing itself.

I claim:

1. In a suction cleaner, a casing, a motor on said casing, a hood about said motor, a lamp between said hood and motor, light transmitting means in said hood for transmitting the light from said lamp forwardly of said casing but preventing entrance of air therethrough into said hood, means in said hood defining a ventilating air passageway for said motor, said light transmitting means forming part of said air passageway, said lamp being in said air passageway, and means for circulating air through said passageway to cool said motor and lamp.

2. In a suction cleaner, a casing, a motor on

said casing, a hood about said motor, means for supporting a lamp between said hood and motor, means defining a port through said lamp supporting means, light transmitting means in said hood for transmitting the light from said lamp forwardly of said cleaner casing but preventing entrance of air therethrough into said hood, means in said hood defining a ventilating air passageway communicating with said port in said lamp supporting means, said light transmitting means forming part of said air passageway, said lamp being in said passageway, and means for circulating air through said passageway and port to cool said lamp and motor.

3. In a suction cleaner, a casing, a motor on 15 said casing, a hood about said motor, a lamp between said hood and motor, light transmitting means in said hood for transmitting the light from said lamp forwardly of said casing but preventing the entrance of air therethrough into 20 said hood, means in said hood defining a ventilating air passageway for said motor, said light transmitting means forming part of said air passageway, said lamp being in said air passageway, means defining a discharge air passageway in said casing and having one end communicating with said ventilating air passageway in said motor hood and its other end terminating in an opening at the underside of said casing adjacent the surface being cleaned, and means for circulating air through said passageways to cool said motor and lamp, said air being discharged below said casing into contact with the surface being cleaned.

4. In a suction cleaner, a casing, a motor on 35 said casing, a hood about said motor, means for supporting a lamp between said hood and motor, means defining a port through said lamp supporting means, light transmitting means in said hood for transmitting the light from said lamp forwardly of said cleaner casing but preventing entrance of air therethrough into said hood, means in said hood defining a ventilating air passageway communicating with said port in said lamp supporting means, said light transmitting means defining part of said air passageway, said lamp being in said air passageway, means in said casing defining an air discharge passageway extending from said port in the lamp supporting means to an opening at the underside of said casing 40 adjacent the surface being cleaned, and means for circulating air through said air passageway, port and discharge passageway to discharge the air beneath said casing at a point adjacent the surface being cleaned, said circulating air cooling said motor and lamp.

5. In a suction cleaner, a casing, a motor on 50 said casing, a housing substantially enclosing said motor and having openings for circulation of ventilating air therethrough, a hood enclosing said housing and spaced from the latter, a lamp between said housing and hood, light transmitting means in said hood for transmitting the light from said lamp forwardly of said casing but preventing entrance of air therethrough into said hood, cooperating means on said hood and housing defining an air passageway between one of said housing openings and to said lamp, said light transmitting means forming part of said air passageway, said lamp being in said air pas-

70 sageway, and means for circulating air through said housing and air passageway to cool said motor and lamp.

6. In a suction cleaner, a casing, a motor on 5 said casing, a housing substantially enclosing said motor and having openings for circulation of ventilating air therethrough, a hood enclosing said housing and spaced from the latter, means for supporting a lamp between said hood and housing, means defining a port through said lamp supporting means, light transmitting means in said hood for transmitting the light from said lamp forwardly of said casing but preventing entrance of air therethrough into said hood, co-operating means on said hood and housing defining an air passageway between one of said housing openings and to said port, said light transmitting means forming part of said air passageway, said lamp being in said air passageway, and means for circulating air through said housing, air passageway and port to cool said motor and lamp.

7. A suction cleaner comprising a casing, a motor mounted on said casing, means for supporting a lamp forwardly of said motor, means defining a port through said lamp supporting means, means defining an air passageway in said casing in register with said port in said lamp supporting means, and means for circulating air over said motor, port and passageway to cool said lamp and motor.

8. A suction cleaner comprising a casing having a nozzle at its forward end, a motor on said casing for rotating a suction creating fan, means for supporting a lamp, means defining a port through said lamp supporting means, said casing having a depending skirt portion spaced from said nozzle to define an open space therebetween exposed to the surface being cleaned, means defining an air passageway in said casing and having one end communicating with said port in said lamp supporting means and its other end communicating with said open space, and means for circulating air through said motor, port and passageway to discharge the air in said open space adjacent the surface being cleaned to cool said lamp and motor.

9. A suction cleaner comprising a cleaner body, a lamp supported by said cleaner body, a hood for said lamp, light transmitting means in said hood for transmitting the light from said lamp forwardly of said cleaner body but preventing entrance of air therethrough into said hood, means forming a ventilating air passageway within said hood, said light transmitting means forming part of said ventilating air passageway, said lamp being in said passageway, and means for circulating air through said passageway to cool said lamp.

10. In a suction cleaner, a casing having wheel pockets, a suction nozzle, means in said casing defining an air passageway having a port open to said wheel pockets and out of direct communication with said suction nozzle, a motor on said casing, and means to force cooling air over said motor through said passageway and port to discharge the motor cooling air into said wheel pockets and out of direct communication with said suction nozzle.
